TYPEWRITING MACHINE

George F. Handley, Glendale, N. Y., assignor to
The Royal Typewriter Company, Inc., New
York, N. Y., a corporation of New York

Application January 13, 1936, Serial No. 58,981

17 Claims. (Cl. 197—82)

This invention relates to new and useful improvements in typewriting machines generally, although more particularly to the carriage escapement mechanism thereof.

5 The principal object of my invention is to provide a carriage escapement mechanism which is fully releasable during the operating stroke of an operating lever such as for instance any key lever or the spacing bar lever, thereby reducing 10 the time heretofore consumed in releasing the escapement mechanism.

In the drawings:

Figure 1 is a vertical sectional view, partly in elevation, embodying my invention,
15 Figure 2 is an enlarged rear elevation of the escapement mechanism,

Figure 3 is a horizontal view partly in section of the escapement mechanism,

Figure 4 is an enlarged vertical section taken 20 through the escapement mechanism,

Figure 5 is a detail perspective view of one end of the universal bar,

Figure 6 is a perspective view of the interponent,

25 Figures 7, 8 and 9 are enlarged detail plan views showing different positions of the interponent during depression of either the spacing bar or any one of the key levers, and

Figure 10 is an enlarged detail section showing 30 one of the universal bar pivots.

Referring to the accompanying drawings, 5 designates an escapement supporting frame of a typewriting machine having a carriage 6 supported thereon in the usual manner. The usual 35 escapement mechanism for the carriage includes a rack 7 which is mounted on the carriage for cooperation with a pinion 8 loosely mounted on a shaft 9 journaled in the frame 5, and fixed to said shaft is the usual escapement wheel 10. A dog 40 rocker 12 is fulcrumed on pivots 13, 13 to swing about a horizontal axis, and mounted on the rocker above the axis thereof are pivoted and fixed dogs 14 and 15 respectively which are successively engaged by the teeth of the escapement 45 wheel 10 when the rocker is rocked to feed the carriage step-by-step in letter space intervals. The rocker 12 is normally held against rearwardly 50 swinging movement by a spring 16 whereby the pivoted or limber dog 14 is normally held in engagement with the escapement wheel 10, the fixed dog 15 being normally disposed in front of said wheel.

A spacing bar 17 is mounted on the front ends of levers 18 (one only being shown) which are 55 fulcrumed as at 19 on a bridge 20 rigidly con-

nected to the side walls of the main frame of the machine, one of said levers terminating in an upwardly extending rock arm 21. In the broad sense, the two levers 18 and the spacing bar 17 constitute a manually depressible lever. A rearwardly extending spring 22 which is connected at one end to the arm 21 and at the other end to a stud 23 fixed to the machine frame, serves to yieldably retain the spacing bar 17 and levers 18 against a stop 18a and against depression. 10

The invention also includes the usual key levers 24 which operate the type bars 25. The type bars 25 are pivotally mounted as at 26 on the segment 27 and each type bar is connected to its associated type lever 24 through the medium of 15 the well known front link 28, a vertical link 29 which connects the key lever with the front link, an intermediate lever 30 which is connected by a link 31 to the front link 28, and a link 32 which connects the intermediate lever 30 with the heel 20 of the type bar. The usual pendant universal bar A is located in rear and below the escapement wheel 10. This universal bar includes spaced legs 33, 33 which are pivoted at their upper ends on noise-reducing rubber insulated 25 bearings as at 34, 34 to bracket arms 35, 35 attached to the main frame 36 of the machine. A plate 37 connects the legs 33, 33 intermediate their ends and a cross bar 38 is supported by the lower ends of the legs below the connecting plate 30 37. One leg 33 is provided with a laterally extending arm 39. A link 40 is connected at its front end to the upwardly extending rock arm 21 and at its rear end to the laterally extending arm 39. Thus when the spacing bar 17 is depressed, the universal bar A will be moved forwardly. Links 41 are connected at their front ends to the intermediate levers 30 and at their rear ends to the cross bar 38 of the universal bar A. Consequently upon depression of any key 40 lever 24 the universal bar A will be moved forwardly. 35

A bracket 42 is attached to the frame 5 at one side of the rocker 12 and a power transmitting lever 43 which extends in a general direction away from the rocker and in a plane parallel to the axis 19, is fulcrumed intermediate its ends on said bracket as at 44, 44 to swing about a vertical axis. The power end 45 is disposed in front of and normally in spaced relation to a 50 forwardly extending and adjustable thrust arm 46 which is secured by a screw 47 to a horizontal arm 48 which is integral with the connecting plate 37 of the universal bar A. Consequently upon forward movement of the universal bar A, 55

either upon depression of any key lever 24 or upon depression of the spacer bar 17, the thrust arm 46 will engage the power end 45 of the transmitting lever 43 and thereby rock the same about its vertical axis. The other end 49 of the power transmitting lever 43 extends laterally toward the feed rocker 12 and is disposed in a plane slightly in front of said rocker. An interponent 50 is fulcrumed intermediate its ends as 5 about 51 on said end 49 of the power transmitting lever and has bodily movement with the latter. The interponent includes a tail 52 at one end and a nose 53 at the other end. The end of the nose 53 is recessed to form a resultant concentric 10 end 54 and a stop 55. A coil spring 56 is connected at one end to the end 49 of the power transmitting lever 43 and at its other end to the tail 52 of the interponent, and serves the dual function of (1) yieldably retaining the tail 52 15 against a stop 57 on the end 49 of the lever 43, and (2) yieldably retaining the concentric edge 54 of the nose 53 of the interponent in engagement with the front face of a laterally extending bearing arm 58 fixed to the upper portion of the 20 dog rocker 12. A fixed abutment 59 which is preferably an integral part of the bracket 42, is located in spaced relation to and in rear of a laterally extending cam arm 60 fixed to the interponent 25 50. It will be observed that the pivot 51 of the interponent is directly in front of the bearing arm 58 of the rocker and that normally the major axis of the interponent lies in a plane at substantially right angles to the general plane of the rocker 12. A coil spring 61 has one end 30 connected to the power end 45 of the transmitting lever 43 and its other end connected to the bracket 42 and functions to yieldably retain the transmitting lever against rocking movements about its vertical axis 44.

40 The universal bar pivots 34, 34 are of noise-reducing construction for the purpose of quieting any universal bar noise which may tend to develop through the action of the universal bar links 41 against the universal bar rod 38, or quieting any noise which may tend to develop by the contact between the thrust arm 46 and either the power end 45 of the transmitting lever 43 or the ribbon lifting mechanism (not shown). To this end, a double flanged bushing 62 with a central hole 63 is positioned within an opening in the upper end of each arm 33 of the universal bar A, said opening receiving the pivot screw 34 which is attached to the bracket arm 35. A steel sleeve 64 having a flange 65 is pushed through 45 the central hole in the rubber bushing until the flange 65 rests against said bushing. A washer or flange 66 is then placed over the outer end of the sleeve 64 and is upset against a shoulder on said sleeve.

50 From the foregoing, it will be observed that during the depression stroke of the spacing bar 17 the universal bar A will be moved forwardly together with the thrust arm 46, the power transmitting lever 43 will be rocked about its vertical axis 44 and against the tension of the spring 61 and the interponent 50 will be bodily moved rearwardly as shown in Figures 7, 8 and 9. The interponent 50 is normally engaged with the dog rocker 12, as shown in Figure 7, and as the interponent is moved rearwardly the cam arm 60 of the interponent will contact the fixed abutment 59 and thereby swing said interponent and disengage the same from the dog rocker, as shown in Figures 8 and 9. This rearward movement of the interponent causes the dog rocker to be

rocked to release the escapement thereby permitting the carriage to be moved one space. The nose 53 of the interponent is abruptly disengaged from the dog rocker and immediately thereafter the power transmitting lever 43 and the interponent return to their normal positions under the influence of the springs 61 and 56 respectively. 5

Thus it will be observed that before the spacing bar reaches the bottom of its depression stroke, or before any one of the key levers reaches the bottom end of its depression stroke, the interponent 50 will have been moved bodily rearwardly to swing the dog rocker 12 to release the escapement and will be subsequently released abruptly from said dog rocker whereby the carriage will be 10 15 fed forwardly one space.

I claim:

1. In a typewriting or like machine, the combination with a carriage, of an escapement mechanism therefor including a dog rocker and a 20 spring for normally holding the rocker against movement, a universal bar, type actions including key levers connected to the universal bar, and means operated by the universal bar during the depression stroke of any key lever for rocking 25 the dog rocker against the tension of the spring and for releasing said rocker.

2. In a typewriting or like machine, the combination with a carriage, of an escapement mechanism therefor including a dog rocker and a 30 spring for normally holding the rocker against movement, a universal bar, type actions including key levers connected to the universal bar, and means operated by the universal bar during the depression stroke of any key lever for rocking 35 the dog rocker against the tension of the spring and for releasing said rocker, said means including a bodily movable and pivotally mounted interponent normally engaging said rocker and movable to disengage said rocker.

3. In a typewriting or like machine, the combination with a carriage, of an escapement mechanism therefor including a dog rocker and a spring for normally holding the rocker against movement, a universal bar, type actions including key levers connected to the universal bar, means operated by the universal bar during the depression stroke of any key lever for rocking the dog rocker against the tension of the spring and for releasing said rocker, said means including a bodily movable and pivotally mounted interponent normally engaging said rocker and movable to disengage said rocker, a spring for normally retaining the interponent in engagement with the rocker, and means disposed in the path of movement of the interponent for swinging the latter out of engagement with the rocker. 40 45 50 55

4. In a typewriting or like machine, the combination with a carriage, of an escapement mechanism therefor including a dog rocker and a 60 spring for normally holding the rocker against movement, a universal bar, type actions including key levers connected to the universal bar, and means operated by the universal bar during the depression stroke of any key lever for rocking 65 the dog rocker against the tension of the spring and for releasing said rocker, said means including a bodily movable and pivotally mounted interponent normally engaging said rocker and movable to disengage said rocker and provided with a cam arm, a spring for normally retaining the interponent in engagement with the rocker, and a fixed abutment mounted for cooperation with the cam arm of the interponent for swinging the latter out of engagement with the rocker 70 75

- during the bodily movements of the interponent.
5. In a typewriting or like machine, the combination with a carriage, of an escapement mechanism therefor including a dog rocker and a spring for normally holding the rocker against movement, a universal bar, type actions including key levers connected to the universal bar, and means operated by the universal bar during the depression stroke of any key lever for rocking the dog rocker against the tension of the spring and for releasing said rocker, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever.
6. In a typewriting or like machine, the combination with a carriage, of an escapement mechanism therefor including a dog rocker and a spring for normally holding the rocker against movement, a universal bar, type actions including key levers connected to the universal bar, and means operated by the universal bar during the depression stroke of any key lever for rocking the dog rocker against the tension of the spring and for releasing said rocker, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever, a spring for normally retaining the interponent in engagement with the rocker, and means disposed in the path of movement of the interponent for swinging the latter out of engagement with the rocker.
- 40 7. In a typewriting or like machine, the combination with a carriage, of an escapement mechanism therefor including a dog rocker and a spring for normally holding the rocker against movement, a universal bar, type actions including key levers connected to the universal bar, and means operated by the universal bar during the depression stroke of any key lever for rocking the dog rocker against the tension of the spring and for releasing said rocker, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever, said interponent being provided with a cam arm, a spring for normally retaining the interponent in engagement with the rocker, and a fixed abutment mounted for cooperation with the cam arm of the interponent for swinging the latter out of engagement with the rocker during the bodily movements of the interponent.
- 65 8. In a typewriting or like machine, the combination with a carriage, of an escapement mechanism therefor including a dog rocker and a spring for normally holding the rocker against movement, a universal bar, type actions including key levers connected to the universal bar, and an interponent located intermediate the dog rocker and the universal bar for rocking the rocker against the tension of the spring and for releasing said rocker during the depression stroke of any key lever.
- 70 9. In a typewriting or like machine, the com-

bination with a carriage, of an escapement mechanism therefor including a dog rocker and a spring for normally holding the rocker against movement, a universal bar, type actions including key levers connected to the universal bar, a spacing bar connected to the universal bar, and means operated by the universal bar during the depression stroke of any key lever or during the depression stroke of the spacing bar for rocking the dog rocker against the tension of the spring and for releasing said rocker.

5 10. In a typewriting or like machine, the combination with a carriage, of an escapement mechanism therefor including a dog rocker and a spring for normally holding the rocker against movement, a universal bar, type actions including key levers connected to the universal bar, a spacing bar connected to the universal bar, and means operated by the universal bar during the depression stroke of any key lever or during the depression stroke of the spacing bar for rocking the dog rocker against the tension of the spring and for releasing said rocker, said means including a bodily movable and pivotally mounted interponent normally engaging said rocker and movable to disengage said rocker.

20 11. In a typewriting or like machine, the combination with a carriage, of an escapement mechanism therefor including a dog rocker and a spring for normally holding the rocker against movement, a universal bar, type actions including key levers connected to the universal bar, a spacing bar connected to the universal bar, and means operated by the universal bar during the depression stroke of any key lever or during the depression stroke of the spacing bar for rocking the dog rocker against the tension of the spring and for releasing said rocker, said means including a bodily movable and pivotally mounted interponent normally engaging said rocker and movable to disengage said rocker, a spring for normally retaining the interponent in engagement with the rocker, and means disposed in the path of movement of the interponent for swinging the latter out of engagement with the rocker.

30 40 12. In a typewriting or like machine, the combination with a carriage, of an escapement mechanism therefor including a dog rocker and a spring for normally holding the rocker against movement, a universal bar, type actions including key levers connected to the universal bar, a spacing bar connected to the universal bar, and means operated by the universal bar during the depression stroke of any key lever or during the depression stroke of the spacing bar for rocking the dog rocker against the tension of the spring and for releasing said rocker, said means including a bodily movable and pivotally mounted interponent normally engaging said rocker and movable to disengage said rocker, a spring for normally retaining the interponent in engagement with the rocker, and a fixed abutment mounted for cooperation with the cam arm of the interponent for swinging the latter out of engagement with the rocker during the bodily movements of the interponent.

50 55 60 65 70 75 13. In a typewriting or like machine, the combination with a carriage, of an escapement mechanism therefor including a dog rocker and a spring for normally holding the rocker against movement, a universal bar, type actions including key levers connected to the universal bar, a spacing bar connected to the universal bar, and means operated by the universal bar during the

- depression stroke of any key lever or during the depression stroke of the spacing bar for rocking the dog rocker against the tension of the spring and for releasing said rocker, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever.
14. In a typewriting or like machine, the combination with a carriage, of an escapement mechanism therefor including a dog rocker and a spring for normally holding the rocker against movement, a universal bar, type actions including key levers connected to the universal bar, a spacing bar connected to the universal bar, and means operated by the universal bar during the depression stroke of any key lever or during the depression stroke of the spacing bar for rocking the dog rocker against the tension of the spring and for releasing said rocker, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever, a spring for normally retaining the interponent in engagement with the rocker, and means disposed in the path of movement of the interponent for swinging the latter out of engagement with the rocker.
15. In a typewriting or like machine, the combination with a carriage, of an escapement mechanism therefor including a dog rocker and a spring for normally holding the rocker against movement, a universal bar, type actions including key levers connected to the universal bar, a spacing bar connected to the universal bar, and means operated by the universal bar during the depression stroke of any key lever or during the depression stroke of the spacing bar for rocking the dog rocker against the tension of the spring and for releasing said rocker, said means including a power transmitting lever mounted to swing about a vertical axis, and an interponent pivotally mounted on and bodily movable with said transmitting lever and normally engageable with said rocker, said interponent being swingable to disengage said rocker upon movement of said transmitting lever, a spring for normally retaining the interponent in engagement with the rocker, and means disposed in the path of movement of the interponent for swinging the latter out of engagement with the rocker.
16. In a typewriting or like machine, the combination with a carriage, of an escapement mechanism therefor including a dog rocker and a spring for normally holding the rocker against movement, a universal bar, type actions including key levers connected to the universal bar, a spacing bar connected to the universal bar, and means operated by the universal bar during the depression stroke of any key lever or during the depression stroke of the spacing bar for rocking the dog rocker against the tension of the spring and for releasing said rocker, said means including a power transmitting lever fulcrumed on the frame to swing about a vertical axis, an interponent mounted on and bodily movable with the transmitting lever to swing about a vertical axis and normally engaging the dog rocker, said interponent being provided with a cam arm, a spring for normally retaining the interponent in engagement with the rocker, and a fixed abutment mounted on the frame and for cooperation with the cam arm of the interponent for swinging the latter out of engagement with the rocker during the bodily movements of the interponent.
17. In a typewriting or like machine, the combination with a carriage, of an escapement mechanism therefor including a dog rocker and a spring for normally holding the rocker against movement, a universal bar, a spacing bar connected to the universal bar, type actions including key levers connected to the universal bar, and an interponent located intermediate the dog rocker and the universal bar for rocking the rocker against the tension of the spring and for releasing said rocker during the depression stroke of the spacing bar or during the depression of any key lever.

GEORGE F. HANDLEY.
